UNITED STATES PATENT OFFICE.

LOUIS M. ASPINWALL, OF PITTSBURGH, PENNSYLVANIA, ASSIGNEE TO WESTINGHOUSE ELECTRIC & MANUFACTURING COMPANY, A CORPORATION OF PENNSYLVANIA.

CONTROL APPARATUS.

Application filed January 20, 1921. Serial No. 438,667.

To all whom it may concern:

Be it known that I, LOUIS M. ASPINWALL, a citizen of the United States, and a resident of Pittsburgh, in the county of Allegheny and State of Pennsylvania, have invented a new and useful Improvement in Control Apparatus, of which the following is a specification.

My invention relates to control apparatus and particularly to electro-pneumatic switches or contactors that are employed for opening and closing circuits.

The object of my invention is to provide a relatively compact contactor which shall be effective and positive in operation and durable in construction.

For a better understanding of my invention, reference should be made to the accompanying drawings,

Figures 1 and 2 of which are views, in side and in end elevation, respectively, of a contactor or electro-pneumatic switch embodying my invention;

Figs. 3, 4 and 5 are views, in end, side and plan elevation, respectively, of a cylindrical member forming part of the valve mechanism of the apparatus shown in Figs. 1 and 2;

Fig. 6 is a cross-sectional view, taken along the line VI—VI of Fig. 3;

Fig. 7 is an inverted plan view of a cap or cover member shown in Figs. 1 and 2;

Fig. 8 is a cross-sectional view of the cover member shown in Fig. 7, taken along line VIII—VIII thereof;

Figs. 9 and 10 are views, in side and in end elevation, respectively, of part of a magnetic blow-out device shown in Figs. 1 and 2;

Fig. 11 is a cross-sectional view taken along the line XI—XI of Fig. 5;

Figs. 12 and 13 are views, in side and in end elevation, respectively, of a part of the contactor shown in Figs. 1 and 2; and

Figs. 14 and 15 are detail views, in side and in end elevation, respectively, of a part of the contactor shown in Figs. 1 and 2.

Referring particularly to Figs. 1 and 2, an integral cylindrical member or casting 1, constituting a part of the magnetic valve mechanism 2, is secured to an insulating base member 3, which may be of slate or any other suitable insulating material. A yoke

member 4 is mounted upon a projecting shelf 5 of the cylindrical member 1 and is 55 insulated therefrom by a sheet 6 of suitable insulating material, such, for example, as micarta. The yoke 4 is secured to the shelf 5 by bolts 7, which are insulated therefrom in accordance with standard practice. The 60 yoke member 4 supports a plurality of core members 8 and of pole-pieces 9, which are illustrated in detail in Figs. 9 and 10. The core members 8 and the pole-pieces 9 are rigidly secured to the yoke member 4 by 65 means of a plurality of tap bolts or screws 11.

A magnetic blow-out coil 12 is mounted upon each of the core members 8, the coils being electrically connected to each other by 70 means of suitable contact strips 13. A stationary contact member or tip 14 is supported by an upper bracket 16 that is positioned between the pole-pieces 9. The bracket 16 is supported by the insulating base member 75 3.

A lower contact member or tip 17 is securely attached to a holder or base 18, which is pivotally mounted upon a lower bracket 19. Stationary arcing horns 21 and 22 are 80 provided for the upper and the lower contact members, respectively. Arc-box sides 23 are mounted between the contact tips 14 and 17 and the pole-pieces 9. The arc-box sides are supported by top and bottom 85 spacer castings 24 and 25, respectively, to which they are secured by means of screws 26.

The spacer castings 24 and 25 are of channel-shape, being of substantially a U-shape, 90 in cross-section, throughout their lengths. The top spacer casting 24 is pivotally mounted upon the upper bracket 16 by means of projecting portions 27, constituting parts of the spacer casting 24, and a bolt 95 28. The lower spacer casting 25 is pivotally mounted upon a hinge piece 29 by means of a bolt 31. The hinge piece 29 is a substantially flat member having a curved end portion 32 enlarged to permit connection 100 with the spacing member 25.

An arcing block 33 is attached to the spacer casting 24 by means of suitable bolts (not shown). A similar arcing block 34 is secured to the lower spacing casting 25. Demountable arc-shields 36 are positioned be-

tween the arc-box sides 23 and the arcing blocks 33 and 34 with the aid of a plurality of arc-box spacers 37, which are best shown in Figs. 14 and 15. The arc-box sides 23 and the arc-box spacers 37 are secured to arcing blocks 33 and 34 by screws 37^a.

By having the spacer castings 24 and 25 pivotally mounted upon the bolts 28 and 31, respectively, the structure, comprising 10 spacer castings 24 and 25, arcing blocks 33 and 34, arc-box sides 23, arc-shields 36, arc-box spacers 37 and arcing horns 21 and 22, may be swung clear of the contact tips 14 and 17 by removing either the upper bolt 28 or the lower bolt 31. This construction permits access to the contact tips 14 and 17 without dismantling a large portion of the contactor.

The pneumatic-valve mechanism 2 comprises the integral cylindrical member or casting 1, an armature member 38 and a magnetizable coil 39.

For a better understanding of the integral cylindrical member or casting 1, reference should be made to Figs. 3, 4, 5, 6 and 11. The casting 1 comprises a hollow portion 41, having projections or bosses 43 and 44, through which it is secured, by suitable screws (not shown), to the insulating base member 3. A projecting cylindrical portion 46 is provided to hold the magnetizable coil 39 and constitutes a part of the magnetic circuit comprising the armature member 38.

The shelf 5, previously mentioned, is shown as provided with bolt holes 47, through which bolts 7 are positioned to secure the yoke member 4 thereon.

As shown, a hollow cylindrical projection 48 is provided on the casting 1 and has formed therein an exhaust port 49 and an inlet port 51. This cylindrical member 48 will be more fully described hereinafter.

Within the hollow cylindrical portion 41 is a cylindrical guide 52 through which the piston rod 53 extends, as best shown in Fig. 11. The piston 54 is mounted upon the lower end of the piston rod 53 and is normally maintained in its lower position by a resilient member or spring 55. The pressure of air upon the lower surface of the piston 54 will cause the piston 54 to rise and compress the spring 55. When pressure is removed from the piston 54, the spring 55 will cause the piston 54 to return to its lower position.

A cap or cover member 56 covers the opening in the base of the hollow member 41. The cap member 56 is secured to the casting 1 by means of bolts 57^a—shown only in Figs. 1 and 2—which extends through the boss portions 57.

Referring particularly to Fig. 6, which shows the method of controlling the air pressure upon the piston 54, the cylindrical

portion 48 of the casting 1 is provided with a hollow chamber 58 extending throughout its length. A valve stem 59 is mounted therein and secured to a movable valve plug or member 61. The valve stem 59 is positioned by the cap member 62, which may be screwed into the opening 58 in the cylindrical portion 48.

A valve plug or member 63 co-operates with a valve seat 64, forming part of a removable cylindrical member 64^a, to control the admission of air from the inlet port 51 to an opening 65 which extends downwardly to the lower face of the casting 1 and permits air to pass therefrom into the hollow cylindrical portion 41. The movable valve plug 61 co-operates with a valve seat 66, constituting a part of the removable cylindrical member 64^a, to control the release of air from the hollow chamber 41, through the vertical port 65, to the exhaust port 49.

A resilient member 67 is provided to maintain the valve member 63 against the valve seat 64, when the valve stem 59 is not actuated by the armature member 38.

Referring particularly to Figs. 12 and 13, the lower contact bracket 19 is securely mounted upon the piston rod 53. The holder or base 18 is pivotally mounted in the bracket 19 by means of a shaft or bolt 70. The base 18 is maintained normally free of the base portion of the bracket 19 by a spring 71, shown only in Fig. 1. The purpose of having the base 18 pivotally mounted is to make the current break occur at the tip of the contact members, thereby keeping the heel free from burning and ensuring a slight wiping action of the contact members 14 and 17.

A boss 72 is provided with an opening 73 to permit attachment of a suitable conductor or shunt that extends from the lower bracket 19 to the cylindrical casting 1 at a boss 73^a, thereby preventing current from passing through the piston rod guide 52. A curved projection 74 of the bracket 19 is provided with a slot 75, which engages a pin that is positioned in a boss 74^a of the casting 1 to prevent the rotation of the piston 53 in the guide 52.

An insulating block or member 76 is mounted upon the projecting portion 74 of the lower bracket 19 by means of screws 77. One or more copper segments or strips 78 are mounted upon the insulating block 76 and form part of an interlock hereinafter described. The copper segments 78, in their upper positions, engage a plurality of auxiliary contact fingers 79, which are best shown in Fig. 2.

The armature 38 shown in Figs. 1 and 2 includes a flexible plate 83 of thin steel or other suitable material attached to a movable plate 81 by means of counter-sunk rivets 84 and a stationary magnetizable

member 82 adapted to be disposed between the plate 83 and the projection 46 of the casting 1, to which one end of the armature is attached by means of a tap bolt 85.

5 An adjustable screw 86 is mounted upon the movable member 81 to actuate the movable valve plug 61 which is within the hollow cylindrical portion 48 of the casting 1. A brass pin 86a, having a T-head, is positioned in the cylindrical portion 48 to limit the outward movement of the movable member 81.

10 The operation of the contactor is begun by energizing the magnetizable coil 39 from an auxiliary or low-voltage control circuit (not shown). This action sets up a magnetic flux through certain switch parts comprising the core member 46, the main body of the casting 1, the hollow cylindrical portion 48, the movable member 81, and the stationary plate 83.

15 The armature member 38 is actuated inwardly against the cylindrical portion 48, whereupon the adjustable pin 86 presses 25 against the movable valve plug 61, which is best shown in Fig. 6. Pressure upon the movable valve plug 61 causes it to actuate the valve stem 59 and to compress the spring 67, thus bringing valve 61 down on its seat 66 and closing the opening from the cylinder 41 to the atmosphere through ports 65 and 49. By the same movement, valve plug 63 is removed from the valve seat 64, and compressed air is permitted to enter from a 35 pipe (not shown) through the inlet port 51 and a portion of the chamber 58 to the port 65 leading to the hollow cylinder 41.

20 The air pressure applied to the piston 54 causes the piston 54 to rise and compress the spring 55 (see Fig. 11). The piston rod 53 is actuated by the upward movement of the piston 54, thereby raising the lower bracket 19. The bracket 19 will rise until the contact member 17 engages the stationary contact member 14.

25 The end of the contact member 17 will first engage the contact member 14 near its free end and, as the upward movement of the lower bracket 19 continues, the base 18 and the contact member 17 will turn on the pin 70 until the contact base 18 comes firmly against the bracket 19. This movement of the contact member 14 gives a wiping action which tends to maintain the contact surfaces of both members clean.

30 The contact member 17 may be lowered by deenergizing the magnetizable core 39, thereby permitting the spring 67 (see Fig. 6) to return the valve member 63 to its closed position, thus effecting communication between the opening 65, leading from the hollow cylindrical member 41, and the exhaust port 49.

35 As soon as the air pressure is removed from the piston 54, the resilient member 55,

as shown in Fig. 11, will return the piston to its lower position, thereby causing the lower bracket 19 to descend.

When the movable contact member 17 engages the stationary contact member 14, 70 a circuit is established from a conductor (not shown) that extends through an opening 87 in the upper bracket 16 and which is secured to the contact member 14 by means of a bolt 88, through stationary contact member 14, movable contact member 17, contact base 18, lower contact bracket 19, conductor 89, which is secured thereto by means of the boss portion 72 shown in Figs. 12 and 13, casting 1, bolts 7, hinge piece 29, 80 strip 90 (shown in Fig. 2), magnetic blow-out coils 12, which are connected to each other, as hereinbefore described, by contact strips 13, and contact strip 91, to contact terminal 92 which is electrically connected 85 to a conductor (not shown) that extends through an opening 93 in a terminal block 94.

When the contact members 14 and 17 are separated, the arc formed therebetween is extinguished by means of the magnetic apparatus comprising magnetizable coils 12, core members 8, tap bolts 11 and yoke member 4. The arc is drawn out along the arcing horns 21 and 22 until it is extinguished. 90 The arcing horn 21 is electrically connected to the stationary contact finger 14 by spacer casting 24, upper bracket 16 and bolts or screws 21, 28 and 88. The arcing horn 22 is electrically connected to the movable contact finger 17 by spacer casting 25, hinge piece 29, bolts 7, cylinder member 1, conductor 89, lower bracket 19 and base 18. 95

100 The operation of the interlock, comprising the contact fingers 79 and the contact strips 78 that are attached to the lower bracket 19, takes place simultaneously with the closing of the contactor and may be made to open or close auxiliary circuits, as desired. 110

115 From the above description, it is apparent that several of the novel features of my invention are:—Employing the valve cylinder to form a part of the magnetic circuit which controls the operation of the armature, the two stationary arcing horns which are always electrically connected to the co-operating stationary and movable contact members, the pivotally mounted arcing shields, and the manner in which the yoke member 120 is mounted upon the valve cylinder. It is evident that, by mounting the yoke member upon the cylindrical or valve member, a material saving in space is effected. By 125 having the arcing horns stationary, the movable contact member or finger may be made lighter, and more massive horns may be employed than if the arcing horn and movable contact finger were one member.

130 While I have shown my invention in a

preferred form, it is apparent that minor modifications may be made in the arrangement of apparatus and circuits without departing from the spirit thereof. I desire, therefore, to be limited only by the scope of the appended claims.

I claim as my invention:

1. The combination with a stationary contact member and a movable contact member, of an arc shield for said members and a plurality of stationary arcing horns electrically connected to said contact members and adapted to co-operate with said contact members, said arcing horns being attached to said shield.
2. The combination with a plurality of relatively movable contact members, of an arc shield for said members and a plurality of stationary arcing horns electrically connected and adapted to co-operate, with said contact members, said arcing horns being attached to said shield.
3. The combination with a movable contact member, of an arc shield for said member, a stationary arcing horn electrically connected to said member and adapted to co-operate therewith upon said member being actuated from its closed to its open position, said arcing horn being secured to said arc shield.
4. The combination with a stationary arcing horn, of a movable contact member electrically connected thereto, and an arc shield for said member, said arcing horn and said member constituting a substantially continuous electrical path upon said member being actuated to its open position and said arcing horn being attached to said arc shield.
5. The combination with a stationary arcing horn having an arcing surface, of a movable contact member having a contact surface and an arc shield for said member, said arcing surface of said horn and said contact surface of said movable contact member constituting a substantially continuous surface upon said member being actuated to its open position and said arcing horn being permanently secured to said arc shield.
6. The combination with a stationary arcing horn, of a contact member, an arc-box therefor, a movable supporting member and means for electrically connecting said

contact member to said horn, said contact member being pivotally mounted thereon and approaching said horn upon said supporting member being actuated to its open position and said arcing horn being permanently secured to said arc-box.

7. The combination with an integral structure comprising a hollow member and a magnetizable core member, of a magnetizable coil mounted upon said core member, a valve mechanism for controlling the supply of air admitted to said hollow member, an armature member coacting with said integral structure and actuating said valve mechanism, a piston within said hollow member and actuated by fluid pressure controlled by said valve mechanism, a plurality of contact members, and an arc-box therefor, one of said contact members being actuated by said piston to engage another of said contact members, and a plurality of stationary arcing horns secured to said arc-box, said contact member that is actuated by said piston being adapted to approach one of said stationary arcing horns upon said contact member assuming its open position.

8. The combination with a magnetizable yoke member, of a magnetizable coil surrounding said member, a plurality of contact fingers, means for protecting said yoke member and said coil from arcing, and means for mounting said protecting means between said yoke member and said contact fingers to permit pivotal movement of said protecting means around either of two axes.

9. The combination with a plurality of contact members, of a yoke member of substantially U-shape, a plurality of core members and of pole-pieces supported by said yoke member, a magnetizable coil mounted upon each of said pole-pieces, a protecting device comprising a plurality of arc-shields and spacer brackets, said device being positioned between said pole-pieces and said contact members, and means for pivotally mounting said protecting device to permit it to be actuated either upwardly or downwardly from its normal position.

In testimony whereof, I have hereunto subscribed by name this 6th day of January, 1921.

LOUIS M. ASPINWALL.
